[57] CLAIM

The ornamental design for a portion of wrapping paper for confectionery product, as shown and described.

DESCRIPTION

FIG. 1 is a top plan view of a portion of wrapping paper for confectionery product, with broken lines shown for illustrative purposes only and forming no part of the claimed design; and,

FIG. 2 is a top plan view thereof, shown without the broken line environmental structure.

The wrapping paper portion is of no appreciable thickness and the undisclosed bottom plan view is flat and unornamented.
